W. G. FOSTER.

Car Brake.

No. 99,424.

Patented Feb. 1, 1870.

United States Patent Office.

WILLIAM G. FOSTER, OF APALACHIN, NEW YORK.

Letters Patent No. 99,424, dated February 1, 1870.

IMPROVED RAILWAY-CAR BRAKE.

The Schedule referred to in these Letters Patent and making part of the same.

To all whom it may concern:

Be it known that I, WILLIAM G. FOSTER, of Apalachin, in the county of Tioga, and State of New York, have invented new and useful Improvements in Car-Brakes; and I do hereby declare that the following is a full, clear, and exact description thereof, which will enable others skilled in the art to make and use the same, reference being had to the accompanying drawings, forming part of this specification.

Figure 1 is an end view of the car D.

Figure 2 is a bottom view of the car D', showing the friction-portions, and vibrating bevel-pinion.

Figure 3 is an end view of the car D'.

Figure 4 is a section of the two cars coupled, the section being taken through the line x x of fig. 5.

Figure 5 is a bottom view of the cars D D'.

Similar letters of reference indicate corresponding parts.

The nature of this invention relates to the braking of a train of cars, by the application of power upon one car of the train.

It consists in certain devices for operating the braking-mechanism of each car, consisting of a spring and chain, in combination with another spring, and in connection with a shaft, upon which said chain is wound, and a lever, which is operated by said springs; also, in the arrangement of two bevel-pinnions, one of which works in a semicircular frame attached to the truck-frame, and the other is secured to a longitudinal shaft under the centre of the car.

In the drawings—

D D' are platform cars, taken to represent any two cars of a train.

A A, &c., are the trucks, and E E, &c., the wheels thereof, keyed on axles F F', &c., all of the usual construction.

The brakes G are connected, by brake-bars H, in the usual manner.

Each pair of brakes of the same car are connected with each other, by means of rods d d', and a brake-lever, e, the said rods being attached to the brake-bars H, and the brake-lever, as shown at fig. 4.

The upper end of the brake-lever is connected with the shaft f of the bevel-pinion a, by means of a chain, g, and spring h.

A spring, h', also serves to withdraw the lever in an opposite direction, when the chain is permitted to unwind from the said shaft f, whereby the brakes G are removed from contact with the wheels E of the cars.

The winding of the chain upon the shaft f is accomplished through the agency of the shaft B, hung in suitable bearings, I, affixed to the trucks in any serviceable manner, and the bevel-pinnions a and b, as

shown, the pinion b being secured to the shaft B, by set-screws, for the purpose of more readily adjusting the brakes to their bearings, as shown.

The connecting-heads J C, of the shafts B B' of each car, are self-coupling, operating on the principle of an universal-joint, as that shown at J and C, so that the shaft B of the car D' will actuate the brakes of all the other cars of the train, by means of the bevel-pinnions a and b, the shaft f, chain g, springs h h', and brake-lever e of each car, which said mechanism is operated by the shaft B, as aforesaid.

The bevel-gearing of the car D' differs from that of the other cars, by the movable character of the shaft of the pinion, and the arrangement of the axes of both pinions, the said axes both being horizontal.

These pinions are lettered a' b'. The pinion b' is keyed on the shaft B, but the pinion a', with which it engages, is provided with reduced ends, one of which has a bearing in the vertical end of the plate K, affixed to the truck, as shown.

The other end of the pinion has a bearing in the lower end of the hand-lever l, shown dotted, whereby the said pinion may be moved, on its inner bearing, as a centre, thus bringing the friction-pinion m, which is affixed to or forms part of the bevel-pinion a', as shown, in contact with the friction-pinion n, on the axle F' of the truck, as shown.

A slotted plate, o, having a slot, o', (see fig. 2,) serves as a guide for the reduced end of the pinion a', for the said reduced end passes through this slot before entering the bearing in the lever l. The plate o is affixed to the truck, as shown.

The pinion a' has sufficient lateral vibration in its inner bearing, in the plate K, to allow it to be brought in or from contact with the friction-pinion n, without any special formation of the said inner bearing; but, in practice, a spherical bearing may be substituted for the one shown, in order to obtain a more correct mechanical operation, if desired.

The brakes are held in contact with the wheel by means of the ratchet and pawl-device, shown at P, q, and r.

In operating these brakes, the lever l is thrown forward, which brings the friction-pinnions m n in contact, and motion is thus communicated to the shafting B B' of the train; and the pinions a' being revolved, the chains g are wound, which actuates the brake-levers B to bring the brake-blocks G upon the wheels, thereby stopping the train.

In practice, the hand-lever, and the pinions a' b', and friction-pinion, may be placed under the tender.

These improvements can be applied to the cars already in use, without altering the construction of them.

I claim as new, and desire to secure by Letters Patent—

1. The spring *h* and chain *g*, in combination with the spring *h'*, when constructed substantially as described, and operating, in connection with the shaft *f* and lever *E*, as and for the purpose set forth.

2. The bevel-pinion *a*, working in the semicircular frames attached to the truck-frame, and the bevel-pinion *b*, secured to the longitudinal shaft *B*, when

each of said parts is constructed, and all are arranged to operate as and for the purpose set forth.

The above specification of my invention signed by me, this 11th day of January, 1868.

WILLIAM G. FOSTER.
